DRILLING RIG SAFETY BRAKE

William B. Driver, Wynnewood, Okla.

Application April 26, 1954, Serial No. 425,633

2 Claims. (Cl. 188—189)

The present invention relates to the oil well drilling industry and more particularly to a safety device for actuating the brake control lever on a rotary drilling rig upon the failure of the "automatic-driller."

A number of the recently developed rotary drilling rigs have been equipped with a control unit which is known in oil field parlance as an "automatic-driller," as above referred to. This device is located adjacent the position the driller usually stands while operating the rig and has operative connections with the controls of the drilling rig, which are usually actuated by hydraulic oil pressure from a pump driven by the source of power for the drilling rig. This "automatic-driller" is used for maintaining a constant rate of feeding the drill pipe into the hole or to regulate the penetration of the drill bit by the amount of weight of the drill pipe. By using this "automatic-driller" in connection with a drilling rig it is not necessary that the driller remain at his post all the time; thus allowing him more freedom during the time it takes for the Kelly-joint to go downward through the rotary table. However one fault of the "automatic-driller" is that the pressure fluid pump is chain driven and when this chain breaks, as happens occasionally, the controls of the "automatic-driller" are then released and the weight of the traveling blocks, swivel and rotary hose unwinds the drilling cable off of the drilling rig drum shaft and all of the above named equipment falls on the derrick floor. The drilling rig keeps turning the Kelly-joint and considerable damage to the drilling equipment results, which may easily run into the thousands of dollars to repair or replace damaged or broken parts.

It is upon such a drilling rig, equipped with an "automatic-driller" that the device of the present invention is designed to be installed to actuate the brake control lever upon the failure of the "automatic-driller." The invention accomplishes this by a governor actuated valve axially mounted to a small wheel, rotatably contacting the periphery of one of the main brake drums of the drilling rig. Upon failure of the "automatic-driller" the rapid rotation of the brake drum spins the small wheel opening the governor actuated valve admitting pressure to a hydraulic cylinder operatively connected to the brake control lever which stops the rotation of the brake drum and the draw works.

Accordingly it is the principal object of this invention to provide a safety device for stopping the unwinding of the drilling line from the drum shaft of a rotary drilling rig equipped with an "automatic-driller" by actuating the brake control lever.

Another object is to provide a safety device of this class which may be adapted for use in connection with any type of rotary drilling rig.

Still another object of this invention is to provide a safety device that is comparatively cheap to manufacture.

Yet another object of this invention is to provide a device that is completely automatic in its operation.

A further object of this invention is to provide a device

2

which may be easily disconnected from the drilling rig when its use is not desired.

Other objects will be apparent from the following description when taken in conjunction with the accompanying two sheets of drawings, wherein:

Figure 1 is a fragmentary elevational end view of the draw works of a rotary drilling rig with the device installed thereon;

Figure 2 is an elevational side view of the device, 10 similar to Figure 1, but on a larger scale to more clearly show the details thereof;

Figure 3 is a perspective view of the device per se; and, Figure 4 is a fragmentary elevational view partly in section, showing the details of a portion of the device.

Like characters of reference designate like parts in those figures of the drawings in which they occur.

In the drawings:

The reference numeral 1 indicates, as a whole, the driller's end of the draw works of a conventional rotary 20 drilling rig.

The reference numeral 2 indicates the main drum at the driller's end of the drum shaft having a brake band therearound, not shown, which is operatively connected to and actuated by a brake control lever 3.

Referring more particularly to Figure 3, the reference 25 numeral 10 indicates the device, as a whole, comprising, a rectangular base plate 11 having an upper surface 9 and a pair of rigid longitudinally extending arms 12 at one end. To the outermost end of each arm 12, respectively, is pivotally attached by bolts and nuts 13 a pair of elongated upstanding strap metal brackets 14, of a selected length, having their upper ends 17 turned at right angles and rigidly connected to a suitable beam 15 of the rig by bolts and nuts 16 (Figs. 1 and 2). To 30 the opposite end of the plate 11 is rigidly attached, preferably as by welding, a pair of spaced-apart depending longitudinally extending alignedly perforated lugs 20. A rod 21, substantially the same length as the spacing of the lugs 20, has its respective ends pivotally disposed 35 axially within the aligned perforations of the lugs 20, as at 22. To one side of the rod 21 adjacent each lug is rigidly attached a pair of parallel bolts 23, perpendicular to the rod 21. A pair of vertically disposed strap iron brackets 24 each have their respective end portions 25 and 26 formed in right angle co-operative parallel 40 relation forming a U-shape. The depending leg end portions 26 are through-perforated to loosely receive the bolts 23, respectively, and are held in slidable relation therearound by nuts 27. The upper leg ends 25 are through perforated for connection with the support 15 by bolts and nuts 28. A metal disc or washer 30 is rigidly connected axially to each bolt 23, respectively, at a selected point spaced from the bracket end 26. A helically wound compression spring 31 is axially disposed 45 around each bolt 23, respectively, between the disc 30 and the bracket end 26 for the purposes more fully explained hereinbelow.

A shaft 35 of a selected diameter and having a length

slightly greater than the width of the plate 11 is rotatably 50 mounted transversely to the upper surface 9 of the plate 11 by rigidly connected suitable bearings 36. A wheel 38, of a selected diameter, is rigidly mounted axially to one end of the shaft 35 in face to face alignment with

the brake drum 2 and with a portion of the periphery 55 of the wheel 38 contacting a portion of the periphery of the drum 2. On drilling rigs which have a protective housing over the brake drum 2, it may be necessary to cut a hole in the housing sufficiently large enough for the wheel 38 to enter and contact the drum edge. The

periphery of the wheel 38 is preferably covered with a band of rubber 39, or the like, to insure frictional contact with the drum 2 for the purposes more fully ex- 60 65 70 75 80 85 90 95

plained hereinbelow. To the opposite end of the shaft 35 is rigidly connected an inertia type governor 40, comprising, an elongated through-perforated rectangular base bar 43 rigidly connected perpendicularly to the shaft 35 through the perforation by a suitable key, not shown, and is held thereon by the washer 41 and the nut 42. The ends of the base 43 are vertically slotted to pivotally receive on pivot pins 46 the ends of a pair of oppositely disposed governor arms 44, each having an enlarged outer end portion 45 (Fig. 4). The arms 44 are held in idle or collapsed position as shown by the solid lines of Fig. 4, by a suitable tension spring 47 connected to each arm 44 and the adjacent side of the washer 41, respectively. Upon the rapid rotation of the shaft 35 by the wheel 38, centrifugal force urges the governor arms 44 to pivot outwardly from the shaft toward the position, as shown in dotted lines (Figs. 3 and 4), for purposes more fully explained hereinbelow.

A conventional quick opening valve-cock 50 having a laterally extending throttle arm 51, slanted downwardly at its free end, as at 52, is threadedly engaged between the ends 53 and 54, respectively, of a hydraulic pressure supply line connected to a hydraulic pump, not shown, of the drilling rig 1. The valve-cock 50 is held in spaced parallel relation above the upper surface 9 of the plate 11 with the throttle arm spaced above the governor 40, by a pair of upstanding suitable split clamps 55 rigidly connected at one end of the upper surface 9 of the plate 11 and gripping the lines 53 and 54, respectively.

A conventional hydraulic cylinder 60 is pivotally connected at its base end 64 to the beam 15 by a pivot pin 61. The piston end 62 of the cylinder 60 is pivotally connected by a pivot pin 63 to the brake control lever 3 adjacent its free end (Fig. 1). The line 54 is connected to the cylinder 60 in a conventional manner. Whenever the drum 2 starts to unwind the drilling line, not shown, by rotation in the direction of the arrow (Fig. 1) due to some mechanical failure of the conventional equipment, the drum 2, being substantially larger circumferentially than the wheel 38, rotates the wheel 38 and shaft 35 very rapidly which actuates the governor 40 by centrifugal force. The enlarged ends 45 of the governor arms 44 being pivoted outwardly by this centrifugal force, contact the downward extension 52 of the throttle lever 51 to open the valve-cock 50. Hydraulic pressure then flows through the line 54 and actuates the cylinder 60 which depresses the brake control lever and stops the rotation of the drum 2. Normally the function of the springs 31 is to urge the plate 11 downwardly to keep the wheel 38 in frictional engagement with the periphery of the drum 2 at all times. Whenever it is desired to operate the drilling rig without the use of the safety brake 10, the following mechanism is provided. A link 65 of a selected length, is pivotally connected at one end between a pair of upstanding ears 66 rigidly connected to the upper surface 9 of the plate 11 adjacent one end 26 of a bracket 24. The free end of the link 65 is provided with a laterally extending hook portion 67 adapted for contact with the upper surface of the end 26 of the bracket 24. The plate 11 is manually pivoted upwardly around the bolts 13 compressing the springs 31 which raises the wheel 38 from contact with the drum 2, as shown by dotted lines Fig. 2, and the link 65 is pivoted upwardly placing the hook portion 67 over the end 26, as shown in dotted lines, Fig. 2. The link 65 then holds the device 10 in an inoperative position until the link 65 is again released.

Operation

The device is installed on a drilling rig in the manner described herein above, and is to be used with an automatic drilling control. If at any time the drilling control mechanism fails, which allows the drilling cable to

unwind off of the cable drum shaft, the drum 2 rotates the wheel 38 and causes the governor 40 to open the valve-cock 50 which actuates the hydraulic cylinder 60 by hydraulic fluid pressure to depress the brake control lever 3 which stops the rotation of the drum 2 and prevents damage to the drilling equipment. When it is desired to use the drilling rig without the device 10 being connected, it may be disengaged from contact with the drum 2 as described hereinabove, and the hydraulic cylinder pivot pin 63 removed, thus allowing conventional operation of the drilling rig 1.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A safety brake for a rotary drilling rig having a rotating brake drum and having a brake control lever, including: a substantially horizontally disposed rectangular plate pivotally mounted at one end on said rig adjacent the periphery of said brake drum; a pair of substantially U-shaped brackets each rigidly connected in depending relation by one leg of the U-shape to said rig above the free end of said plate disposing the depending leg of said bracket in spaced parallel relation above the free end of said plate, the depending leg of each said bracket having a perforation intermediate its ends; a pair of bolts pivotally connected at one end to the free end of said plate, said bolts slidably connected to the respective depending legs of said brackets through said perforations for permitting vertical movement of the free end of said plate toward and away from said brackets; a helical spring axially disposed around each said bolt for normally urging the free end of said plate away from said brackets; a shaft rotatably carried transversely by the upper surface of said plate in axial parallel relation with said drum, the length of said shaft being greater than the width of said plate; a wheel axially mounted on one end of said shaft in rotatable peripheral contact with said brake drum; an inertia governor axially carried by the end of said shaft opposite said wheel; a hydraulic cylinder pivotally connected at each end to said rig and said brake control lever, respectively, said cylinder having a hydraulic supply line extending longitudinally across said plate; a pair of clamps rigidly carried in longitudinal spaced-apart relation by the upper surface of said plate for holding said supply line in spaced parallel relation above said plate; and a quick-opening valve in said supply line between said clamps, said valve having a laterally extending handle normally projecting toward the extended rotating path of said governor when said valve is in closed position, whereby rapid rotation of said brake drum revolving said wheel actuates said governor for contacting and moving said valve handle to open position for actuating said cylinder and depressing said brake lever thereby stopping the rotation of said brake drum.
2. Structure as specified in claim 1 and a latch pivotally connected at one end to the upper surface of said plate adjacent the depending leg of one said U-shaped bracket, said latch having a hook-shaped free end for engagement with the upper surface of the depending leg disposing the periphery of said wheel in spaced-apart relation with said brake drum for inactivating said safety brake.
